UNITED STATES PATENT OFFICE.

LUTHER J. ADAMS, OF MELROSE, ASSIGNOR TO THOMPSON, PERLEY & WAITE, OF BALDWINSVILLE, MASSACHUSETTS.

CHILD'S CHAIR OR CARRIAGE.

SPECIFICATION forming part of Letters Patent No. 398,304, dated February 19, 1889.

Application filed May 4, 1885. Serial No. 164,267. (No model.)

To all whom it may concern:

Be it known that I, LUTHER J. ADAMS, of Melrose, county of Middlesex, State of Massachusetts, have invented an Improvement in 5 a Child's Chair or Carriage, of which the following description, in connection with the accompanying drawings, is a specification, like letters on the drawings representing like parts.

10 This invention has for its object the production of a simple and efficient chair, which may be readily used either as a high chair or as a carriage.

In accordance with my invention a base-frame equal in length to the height of the high chair below the seat and provided at its front side intermediate its ends with two pairs of 15 rolls has pivoted to it a seat, the connections or links joining the seat with the base-frame 20 being such as to permit the said seat to rest on the ends of the legs of the base-frame when in upright position and to be turned backward when the base-frame is turned over upon its front side or upon its wheels, 25 the said seat resting on the then upper but really the rear side of the base-frame.

The particular features in which my invention consists will be hereinafter described, and pointed out in the claims at the end of this 30 specification.

Figure 1 in side elevation represents a child's chair and carriage embodying my invention, the parts being in the position for use as a high chair; Fig. 2, a side elevation of my improved chair, the parts being in position for 35 use as a carriage; and Fig. 3, a front elevation of Fig. 2.

The base-frame is composed, essentially, of four legs or corner-pieces, A A B B, joined 40 together by suitable rounds or rungs, a b c d e f, as ordinarily practiced in chair-making. The front legs, A, have studs 2, on which are placed two wheels, C C, while studs 3 carry or support two wheels, D D. When the base-frame is to be used to support the seat E for 45 a high chair, the said frame will be placed in upright position, as in Fig. 1, and the ends of the legs A B will stand upon the floor; but when the base-frame is to serve to support 50 the seat for the purpose of a carriage the said

base-frame will be overturned upon its front side, placing the rollers C D upon the floor, as in Fig. 2. The seat E, having a suitable back and arms, is provided at each side with an ear, g, which has pivoted to it at 4 a link, h, 55 the opposite end of which is jointed or pivoted at 5 to the back legs, B B. The seat E at its front side is provided with a foot-rest, F, the arms f² of which, when the seat is as in Fig. 1, rest with their rear sides against the round e. When the base-frame is turned over from its position, Fig. 2, the seat is turned or carried over toward and so as to rest against the back of the base-frame, as in Fig. 2, the seat and link then occupying the position 60 shown in Fig. 2, the rear sides of the parts f² then coming against the round f. The seat does not, as heretofore, have attached to it short seat-legs, which at times rest upon the floor and at other times rest upon the base of 70 the frame.

I do not desire to limit my invention to links or connections h of the exact shape shown in the drawings.

The round or rung d serves as a fulcrum for 75 the trundling-handle m, the latter, when the base-frame is in its upright position, being folded in close to the legs B B. The seat is entirely free to be moved into position to rest either on the end of the seat-frame or on its 80 side, and when in the latter position the ears g come against the legs B B between their ends and the parts f² rest against the round f, thus keeping the seat in horizontal position, although the legs B B are then in inclined position.

I claim—

1. The convertible child's chair and carriage comprising a base-frame composed of front and rear legs, A B, connected in pairs 90 by rounds, and the pairs rigidly connected together, and one pair having rollers, combined with the seat, the ears g, secured to the seat, and links h, jointed to the said ears and to one pair of legs, whereby the seat may be 95 shifted to rest upon the legs when upright and upon one side thereof when the legs are supported sidewise upon their rollers, substantially as described.

2. The combination of the two pairs of legs, 100

- A B, rigidly connected by rounds, including rounds *e* and *f*, the seat E, the ears rigidly attached to the under side of the seat-bottom, the links *h*, pivoted to said ears and to the legs B, for adjusting the seat from the upper ends of the legs when upright to one of their sides when the base-frame is laid down lengthwise, and the foot-rest co-operating with the round *e* to hold the seat in position with the base-frame upright, and also co-operating with the round *f* and the ears *g* in the engagement of the latter with the legs to hold the seat in position when the base-frame is horizontal, substantially as described.
- 15 3. A convertible high chair or carriage composed of a rigid base-frame provided at its front side with wheels or rollers and a seat and foot-rest, the seat being connected with the base-frame by links, whereby the seat may be turned into position to rest either directly upon the ends of the base-frame or upon the rear side of said base-frame placed uppermost by turning the base-frame over with the rollers at its front side on the floor, substantially as described.
- 20 4. The base-frame and the attached rollers and the seat, combined with the links connecting the seat with the rear part of the base-frame below its upper end, substantially as described.
- 25 5. The base-frame, its attached rollers, and the seat provided with depending ears, combined with the links connecting the said ears with the base-frame, substantially as described.

6. The base-frame, its attached rollers, and the trundling - handle pivoted to the base-frame near its lower end, and the seat, combined with the links joining the seat and base-frame, the links being connected with the 40 said base-frame at a point below its upper end, to operate substantially as described.

7. The base-frame having the rounds *e* and *f* and the seat and its attached arms *f*², combined with the links *h*, connecting the seat 45 with the base-frame, the arms *f*², resting against the round *e* while the base-frame is upright and against the round *f* when the base-frame is turned over, substantially as described.

8. A convertible chair composed of a base-frame constructed of pairs of front and rear legs of substantially equal height rigidly connected, and a seat joined to said frame by links, and thereby adapted to be placed in 55 position upon the upper ends of said base-frame when it is upright and to be turned over and supported upon one of the pairs of legs when said base-frame is turned down lengthwise, combined with wheels or rollers 60 to support the base-frame when in this last-named position, substantially as described.

In testimony whereof I have signed my name to this specification in the presence of two subscribing witnesses.

LUTHER J. ADAMS.
